Specification of Letters Patent. Patented Apr. 23, 1918.

Application filed February 15, 1917. Serial No. 148,888.

To all whom it may concern:

Be it known that I, DALMAR T. BROWNLEE, a citizen of the United States, residing at Indianapolis, in the county of Marion and State of Indiana, have invented a new and useful Starter, of which the following is a specification.

The object of my invention is to produce an improved form of starting mechanism, by 10 means of which a motor, such as an internal combustion engine, may be set into motion by a small electric motor, the construction being such that the connection between the starting motor and main motor may be automatically established and disestablished.

The accompanying drawings illustrate my invention.

Figure 1 is a side elevation of one form 20 of the connecting gearing, in dissociated position, with fragmentary adjacent portions of the starting motor and started motor; Fig. 2 is a similar view of another form of my invention; and Fig. 3 a diagrammatic view of the starting motor and the controlling switch.

In the drawings, 10 indicates the starting motor having armature 11, field 12, field coils 13, in which battery 14 is in circuit, and a short circuiting resistance circuit 15 connected to the armature. The resistance circuit 15 at one end terminates in a terminal 16, and the battery circuit terminates at one end in a terminal 17. Arranged to coöperate with one or the other of these terminals 16 30 and 17 is a switch 18 which is connected by wire 19 to the armature circuit. A spring 21 serves to normally keep switch 18 in contact with terminal 16, thus short-circuiting the armature through the resistance circuit 15, 40 and a pedal 22 is carried by switch 18 so that the switch 18 may be swung from terminal 16 to terminal 17.

The starting motor 10 is provided with a shaft 24 upon which is splined a spiral gear 25 which is backed by a spring abutment 26, so as to permit a slight axial movement of the gear 25 in one direction upon its shaft 24. In the form shown in Fig. 1, the abutment 26 is placed beyond gear 25 and held in 50 position by collar 27, whereas in the form shown in Fig. 2, the abutment is placed between the gear 25 and the casing of the motor 10.

Arranged parallel with shaft 24 is a stud 29 upon which is journaled a spiral gear 30

which meshes with gear 25, said gear being freely rotatable and axially movable upon stud 29, the axial movement being limited in one direction by the motor casing, and in the other direction by collar 31. The spiral gear 30 carries a spur pinion 32 which is capable of meshing with gear 33, carried by, or connected to, the motor which is to be started, said gear conveniently being carried by, or formed upon, fly wheel 34 of the 65 motor to be started.

The direction of pitch of the spiral teeth of gear 25 depends upon the direction in which the gear 32 is to be shifted axially in order to be brought into mesh with gear 33, 70 as indicated in Figs. 1 and 2, and the abutment 26 is so placed that, when gear 32 meets the resistance of gear 33, gear 25 may have a slight axial yielding upon its shaft, thereby avoiding the shock which would otherwise occur.

In operation, a depression of the pedal 22 forces switch 18 into contact with terminal 17, thus completing the battery circuit and setting the motor 10 into operation, rotating 80 shaft 24 in the direction indicated by the arrows in Figs. 2 and 3. The slight resistance offered by gear 30 to rotation under a driving force applied by gear 25, causes the gear 30 to shift axially upon stud 29 and to drive 85 gear 32 into engagement with gear 33. The meshing of gear 32 with gear 33 places the motor under the sudden load of the gear 33 and its connected parts so that if the gear 25 were axially unyielding, the starting motor would be jarred. The abutment spring 26, however, permits the gear 25 to momentarily shift axially so as to avoid this jar- 90 ring, and, as the gear 33 acquires velocity under the driving effect of the motor 10, 95 spring 26 will return the gear 25 to its initial position. As soon as the started motor is driven under its own power, the speed of gear 33 will be considerably in excess of the speed of gear 32 under the driving force of 100 motor 10 and consequently, because of the interaction of the two spiral gears 25 and 30, the gears 30 and 32 will be shifted axially so as to cause gear 32 to be withdrawn from gear 33. As soon as the started motor has 105 begun to operate under its own power, the operator will release switch 18 so that spring 21 may swing it into contact with terminal 16, thus cutting out the motive current for motor 10, and at the same time closing the 110

armature circuit through the resistance circuit 15, so as to cause a sudden stoppage of the shaft 24, this sudden stoppage materially assisting in the automatic withdrawal of 5 gear 32 from gear 33.

I am aware that starting devices embodying an axially shiftable gear shifted by the coaction of threaded parts have been commonly in use, but in practice it is found 10 that if these threaded parts are a sufficiently tight fit to prevent accidental meshing with the gears, then the unavoidable accumulation of dirt upon the threaded members often prevents the shifting operation, be- 15 cause the axial shifting is entirely dependent upon the inertia of the shifting element. In my present construction, gears 25 and 30 may very closely and accurately fit each other and the bore of gear 30 may closely 20 fit pin 29, so that any accumulation of dirt upon the exposed portion of pin 29 will not in any way prevent the positive shifting of the gear 32 into, or out of, mesh with gear 33.

25 In view of the fact that stud 30 has no rotative movement, it will be apparent that any condition of this stud, which offers an increased resistance to the rotative movement of gear 30 will act merely to insure 30 the projection of this gear axially on the stud, because no material rotative force can be transmitted through gear 30 until its axial movement is positively arrested after pinion 32 has been brought into mesh with 35 gear 33.

I claim as my invention:

1. A motor starting apparatus comprising two meshing spiral gears, one to be driven by the starting motor and capable of 40 limited axial movement against the action of a yielding abutment and the other to be connected to the motor to be started, the said yielding abutment, a spur gear carried by the other of the spiral gears, a support 45 for said other spiral gear and the associated spur gear, said support permitting both rotative and axial movement of the connected spiral and spur gears, said axial movement from normal being in the direction of ac- 50 tion of the spring abutment.

2. A starting device comprising an electric motor, a spiral gear driven by said motor and capable of limited axial movement,

a yielding abutment opposing said axial movement, a second spiral gear meshing 55 with the first-mentioned spiral gear, and mounted for axial movement, means to limit said axial movement, a spur gear carried by said second spiral gear, controlling circuits for said motor comprising an energizing 60 circuit and a braking circuit, and a switch for alternately opening and closing said energizing circuit and braking circuit.

3. A starting device comprising an electric motor, a spiral gear driven by said motor, a second spiral gear meshing with the first mentioned spiral gear, and mounted for axial movement, means to limit said axial movement, a spur gear carried by said second spiral gear, controlling circuits for said 70 motor comprising an energizing circuit and a braking circuit, and a switch for alternately opening and closing said energizing circuit and braking circuit.

4. A starting device comprising an electric motor, a rotative transmitting element automatically shiftable into effective position by movement of the motor under its own power, and shiftable to ineffective position by the application of an external 80 driving force at a higher velocity, an energizing circuit for said motor, a braking circuit for said motor, and a switch for alternately opening and closing said energizing 85 circuit and braking circuit.

5. The combination with an internal combustion engine provided with a rotative member to which an external driving force may be applied, an electric starting motor, a rotative transmitting element automatically shiftable into effective engagement 90 with the rotative element of the internal combustion motor by movement of the electric motor under its own power, and shiftable to ineffective position by the driving 95 force applied by the internal combustion engine at a higher velocity, an energizing circuit for said electric motor, a braking circuit for said electric motor, and a switch for alternately opening and closing said energizing circuit and braking circuit.

In witness whereof, I have hereunto set my hand at Indianapolis, Indiana, this tenth day of February, A. D. one thousand nine hundred and seventeen.

DALMAR T. BROWNLEE.
